UNITED STATES PATENT OFFICE.

ELGAR R. BAINTER, OF GOOD HOPE, OHIO.

ROLLER.

1,087,345.

Specification of Letters Patent.

Patented Feb. 17, 1914.

Application filed January 29, 1912. Serial No. 674,181.

To all whom it may concern:

Be it known that I, ELGAR R. BAINTER, a citizen of the United States, residing at Good Hope, in the county of Fayette and State of Ohio, have invented certain new and useful Improvements in Rollers, of which the following is a specification.

My invention relates to rollers and is particularly directed to an improvement in rollers for use in breaking clods of earth, but desirably of such a nature that the earth being operated upon will not be packed too closely which is undesirable under certain circumstances, such as in the treatment of farm lands. In the attainment of such a roller, I have constructed my roller with a central hollow which does not detract from the necessary strength of the roller, but gives it sufficient lightness to preclude the packing mentioned.

My invention further contemplates the provision of end reinforcing elements for the roller utilized, which end reinforcing elements are desirably flush with the rolling surface of the roller and secured with sufficient rigidity thereto to preclude chipping or breaking of the edges of the roller.

Still a further object of my invention is to form the body of the roller about a core of strawboard or similar material, similar in the sense that it must be light and inexpensive.

The preferred embodiment of my invention is shown in the accompanying drawings, in which similar characters of reference designate corresponding parts, and in which—

Figure 1 is a plan view of my roller structure wherein there are utilized dual rollers, but having the same essential characteristics of a single roller and showing one of the rollers in longitudinal horizontal section, Fig. 2 is a section taken on line 2—2 of Fig. 1, Fig. 3 is a section taken on line 3—3 of Fig. 1, and Fig. 4 is an end view of the structure shown in Fig. 1.

In the drawings, there is shown an angle iron framework of rectangular form and comprising transverse members 1, longitudinal rods 2, embracing longitudinal rod 3 and a bracing center piece and bearing 4. The framework carries a handle 5 which is desirably bolted thereto as at 6 and 7. This produces a strong framework member and 55 this member carries depending trunnions 8 upon its transverse pieces, which depend-

ing trunnions serve to support bearings 9 which are of any desired and essential form.

Extending longitudinally of the frame through all of the bearings carried by the 60 trunnions as mentioned, is a shaft 10 held against rotation by set screws as shown at 11 in Fig. 4.

The rollers are identical in structure and will be described accordingly. Each roller 65 comprises a hollow cylindrical central core 12 of strawboard, and a surrounding body of concrete 13 desirably reinforced at its ends by triangularly disposed reinforcing rods 14 which are preferably in the form of 70 twisted rectangular bars of metal. The ends of the body portions of these rollers are braced and reinforced by disk-like plates 15 having annular undercut flanges 16 upon their inner peripheral edges which are in 75 turn broken at intervals by dove-tail lugs 16a. This structure of undercut flanges and dove-tail lugs is peculiarly efficacious in forming a firm anchorage connection between the concrete and the disk plates. The 80 plates are further provided centrally with frusto-conical formations 17 which are bored, and being concentrically disposed and concentrically bored, serve as extended bearings for the rollers upon the shaft 10 85 preventing uncertainty of rotation and wabbling liable to result from wear of the parts of a roller of this structure. These plates being anchored to the concrete body portion as aforesaid, are further held in rigid position by longitudinal bars 18 and nuts 19.

From the above, it will be apparent that I have provided a simple structure of roller which may be used either in dual form or in single roller form, but which is essentially 95 compact and strong and will not readily lose its centered and proper position of operation. Furthermore, the parts are so formed structurally and so related to each other as to insure against accidental separation or 100 breakage due to stress of work.

What I claim, is—

1. A roller structure comprising a monolithic roller element, a light hollow core for said element, cap plates having integral extended bearings for said element, annular undercut flanges formed on the peripheral edges of said cap plates, said bearings and flanges being embedded in the ends of the roller element.

2. A roller structure comprising a monolithic roller element, a light hollow core for

said element, cap plates having tapered integral extended bearings for said element, annular undercut flanges formed on the peripheral edges of said cap plates, spaced 5 dove-tailed lugs on said flanges, said lugs, flanges and bearings being embedded in the ends of the roller element.

3. A roller structure comprising a monolithic roller element, a light hollow core for 10 said element, reinforcing bars in the ends of said element extending from the ends of said element to the ends of the core, cap plates having integral extended bearings for said element, an operating shaft extending 15 through said element and said bearings, complementary apertures in said element for receiving said bearings and rods extending through said element and said plates for holding said plates in position.

4. A roller structure comprising a monolithic roller element, a light hollow core for 20 said element, cap plates having extended bearings for said element, annular undercut flanges on the peripheral edges of said plates, spaced dovetailed lugs on said 25 flanges, an operating shaft extending through said roller element and said bearings, rods extending through said roller element and said cap plates for holding said cap plates in position, said bearings, flanges 30 and lugs being embedded in the ends of said roller element.

In testimony whereof I affix my signature in presence of two witnesses.

ELGAR R. BAINTER.
